Kevin D. Jablonski

(57) **CLAIM**

The ornamental design for a straw as shown.

DESCRIPTION

FIG. 1 is a perspective view of the straw.

FIG. 2 is a bottom perspective view of the straw.

FIG. 3 is a top view of the straw.

FIG. 4 is a front view of the straw.

FIG. 5 is a bottom of the straw.

FIG. 6 is a back view of the straw.

FIG. 7 is a right-side view of the straw; and,

FIG. 8 is a left-side view of the straw.

The subject ornamental design is for a straw (see FIG. 1) having a solid body.

1 Claim, 3 Drawing Sheets
